UNITED STATES PATENT OFFICE.

OTTO SPAHR, OF PHILADELPHIA, PENNSYLVANIA, ASSIGNOR TO STRAUSE GAS IRON CO., OF PHILADELPHIA, PENNSYLVANIA, A CORPORATION OF PENNSYLVANIA.

SELF-HEATING SAD-IRON.

1,177,576.

Specification of Letters Patent. Patented Mar. 28, 1916.

Application filed May 5, 1915. Serial No. 25,884.

To all whom it may concern:

Be it known that I, OTTO SPAHR, a citizen of the United States, and a resident of Philadelphia, county of Philadelphia, State of Pennsylvania, have invented certain new and useful Improvements in Self-Heating Sad-Irons, of which the following is a specification.

My invention relates to self-heating sad irons and has for its object to provide such irons with an improved hinged or pivoted cover construction and with an efficient and simple locking means whereby said cover is locked in its closed position to the body and is readily detachable therefrom when it is desired to move said cover to its open position.

A further object of my improvement is to so locate said locking means that the same is entirely invisible when the cover is closed whereby the appearance of the iron is materially enhanced and the locking means itself is protected against interference and tampering.

My invention also contemplates the improvement of the bottom construction of the body in a manner to secure a maximum heating effect from the flames of the burner.

The details of my improvement will be fully set forth in the description hereinafter and the features of novelty will be pointed out in the appended claims.

In the accompanying drawings which illustrate an example of my invention, Figure 1 is a plan view of my improved iron with parts broken away; Fig. 2 an inverted plan view of the cover; Fig. 3 is a cross section on the line 3—3 of Fig. 1; Fig. 4 is a detail section on the line 4—4 of Fig. 3, and Fig. 5 is a detail view of the locking member.

As shown in the drawing my improved construction comprises a hollow body 10 which in the example shown is provided in its bottom with a channel 11 extending lengthwise of the iron and connected with the atmosphere by means of passages 12 extending transversely through said bottom as shown in Fig. 3. In the preferred construction the interior surfaces 13 of the bottom at opposite sides of said channel incline downwardly therefrom toward the outside as also shown in Fig. 3, the purpose of which will appear more clearly from the description hereinafter. At its upper edge the body in the illustrated form is provided with

end projections 14 and lugs 15 and 16 located intermediate thereof and opposite each other whereby openings 17 are formed through which the products of combustion may readily escape from the iron during use thereof. A burner 18 provided with oppositely and downwardly directed jet apertures 19 is located in said body 10 above and in registry with said channel 11 and in the example illustrated is continued exteriorly of the body in the form of an upwardly inclined tube 20. The latter is provided with the usual air inlet openings 21 and terminates at its upper end in a preferably detachable nipple 22 adapted to accommodate one end of the usual fuel tube whereby the burner is connected with a source of fuel supply in the usual manner.

A cover 23 having the same general shape when looked at in plan as the body 10 when similarly viewed is provided for closing said body at the top. This cover 23 is movably connected with the iron for instance by being hinged on or pivotally connected with the lug 15 as shown at 24 in Fig. 3 and in this case is pivotally movable in a vertical plane to and from a closed position. The said cover 23 is further provided with projections 25 on which a plate 26 preferably of metal and more or less elastic is positioned so as to be spaced from the cover whereby an air space 27 is formed between said plate and cover throughout substantially the entire area of the latter. The said plate 26 may be secured to the cover in any suitable manner as by screws 28 which may also serve to secure the handle 29 whereby the iron is manipulated to the cover, washers or the like 30 being preferably located about said screws between said handle and said plate.

In order that the cover 23 may be securely locked in its closed position I provide a latch or dog 31 which projects through an aperture 32 in the cover 23 and is formed with transversely projecting shoulders 33 arranged to rest upon the upper surface of said cover on opposite sides of said aperture 32 as shown in Fig. 4. The upper end surface 34 of said dog or latch 31 is flat and in the assembled condition of the parts engages the lower surface of the plate 26, which exerts a pressure upon said flat end surface, whereby said dog or latch is normally maintained in its operative position.

under the pressure exerted by said plate as shown in Fig. 3. With this arrangement it will be seen that the latch or dog 31 is in the nature of a separate element set into the aperture 32, it being of course understood that in some cases said dog 31 may be attached to and depend from said plate 26 through said aperture 32. In this latter instance the resiliency of the plate will maintain the latch or dog in its operative position. The lower end of said latch or dog 31 is formed with a nose or projection 35 adapted to enter a recess 36 in the lug 16 when the cover is closed and in coöperation with said recess serves to firmly lock the cover in its closed position. The lower portion of said nose or projection 35 is preferably rounded as at 35^a while its upper portion 35^b is preferably curved or rounded transversely when looked at as in Fig. 4, the recess 36 being preferably circular with its inner surface diverging toward its open end as shown in Fig. 3. The wall 32^a of the aperture 32 at its upper edge substantially engages the dog 31 and then preferably inclines away therefrom as shown in Fig. 3 whereby said dog is prevented from sliding in the aperture 32 relatively to the plate 26 and cover 23 toward the longitudinal center 30 of the iron and the projection 35 is prevented from unintentionally leaving the recess 36 as would be possible if the aperture 32 at its upper edge were dimensioned so as to permit such sliding movement of the dog. At the same time the inclination of the wall 32^a permits said dog to rock on the shoulders 33 away from the recess 36 when the cover is being opened. In other words when the dog or latch is a separate element 40 as described the aperture 32 at its upper edge, at least, is preferably so proportioned relatively to the dog 31 as to prevent any substantially loose sliding movement of the latter in said aperture in directions parallel 45 with the plane of the cover, whereby a relatively firm, secure arrangement is provided. This locking means is entirely automatic in action and needs no individual or manual actuation when it is desired to either lock 50 the cover in its closed position or to open it. For instance when the cover is closed as in Fig. 3 and it is desired to open it all that is necessary is to exert a force on the handle 29 tending to swing said cover 23 55 on the pivot 24 relatively to the body to an open position. This force will cause the upper portion 35^b of the projection 35 to ride along the diverging inner surface of the recess 36 and will consequently swing the lower end of the latch or dog 31 inwardly or in other words rock said dog upon the shoulders 33 which rest on the cover 23 and which thus serve as a pivot or fulcrum 60 during this operation, the inclined wall 32^a permitting such rocking movement of said

dog out of the recess 36 as will be readily apparent. This inward swinging or rocking of the dog will be resisted by the plate 26 which rests on the flat end surface 34 of the dog or latch so that the force must be sufficient to overcome the pressure exerted by said plate, it being of course understood that the body is held against movement in any suitable way during this operation, as by grasping the tube 21. As soon as the projection 35 has passed completely out of the recess 36 the cover 23 is free to be swung to its completely open position without difficulty. During the rocking of the dog as described, the flat end surface 34 of the dog 31 will assume an angle relatively to the lower surface of the plate 26 and will thus slightly bend said plate upwardly against its pressure. As soon as the projection 35 has passed beyond the lug 16 the pressure of the plate 26 will immediately force the end surface 34 of the dog 31 back into surface engagement with the lower face of said plate and will thus rock the dog on the shoulders 33 in the reverse direction so as to immediately return the latch or dog 31 to its initial position. In swinging the cover on its pivot in the opposite direction to again close it the lower rounded end 35^a of the latch or dog 31 will engage the lug 16 and will again be swung inward thereby or rocked on the shoulders 33 against the pressure of the plate 26 in the same manner as above described, and as the closing movement of the cover is continued will finally be snapped 105 into the recess 36 to again firmly lock the cover against movement relatively to the body. Instead of arranging the dog 31 as a separate element, the said dog may, as before indicated, be attached to and depend 110 from the plate 26 through the aperture 32. In this case the plate will simply yield and carry the dog with it as pressure is applied to open or close the cover and the resiliency of said plate will serve to snap the projection 35 into the recess 36 and hold the same 115 therein when said cover is fully closed. With this latter arrangement the dimensions of the aperture 32 are not material excepting that they must be such as to permit a yielding movement of the dog when the cover is being opened or closed, it being also possible in this case to omit the shoulders 33 if desired. The pressure exerted by the plate 26 on the surface 34 of the latch or dog 31, if the latter is loosely connected therewith or the resiliency of said plate if the dog depends therefrom, is sufficient to maintain the projection 35 firmly seated in the recess 36 under ordinary conditions so that the iron 120 may be freely lifted by the handle or otherwise manipulated during use without disengaging the locking means and without danger of causing an unintentional opening of the cover. Owing to the fact that the lock- 125

ing means itself in either case needs no individual manipulation to lock or release the cover and is actuated entirely through the medium of the latter, the said locking means 5 may be located on the inside of the iron parts and so as to be substantially invisible when the cover is closed. In this way the appearance of the iron is materially improved and no inconvenient exterior projections 10 are present therein and at the same time the locking means itself is protected against interference and tampering and against accidental or unintentional actuation. With the present arrangement the 15 means for maintaining the latch or dog in its operative position is located exteriorly of the cover away from the direct influence of the flames at the burner and with the cover forms an air space which insulates 20 said means or more specifically the plate 26 against the heat radiating from the cover. At the same time the handle 29 is also protected against such heat radiation with this construction which has the additional advantage 25 of confining the radiation of heat to such parts of the iron which it is intended to heat. By pivoting the cover 23 about a horizontal pivot so as to swing in a vertical plane and combining same with the automatic locking means referred to it is possible 30 to readily swing the cover to its open position during such periods when the iron is temporarily at rest during use. As shown by dotted lines in Fig. 3 the handle 29 in this open position of the cover is entirely 35 outside of the zone in which the heat radiates from the iron so that said handle may in this manner be kept perfectly cool thus doing away with the necessity for the use of an iron holder or the like.

By inclining the surfaces 13 of the bottom of the iron downwardly toward the outside, these surfaces extend in the same general direction as the flames issuing from the jet 45 openings 19, which flames in consequence are not broken up but extend transversely in contact with said surfaces throughout and with full force thus bringing about a maximum heating effect in a minimum of time. 50 With the arrangement described it is also possible to maintain the iron in the desired heated condition with much smaller flames than heretofore thus resulting in a reduction in the consumption of fuel.

My improved arrangement is very simple in construction and provides an iron of maximum efficiency, it being understood that the cover and locking means may be combined with iron bodies of other shapes and 60 constructions than the one shown without affecting the efficiency of said cover and locking means, and also that the illustrated arrangement may be otherwise varied to meet the requirements of any particular case.

Various changes in the specific forms

shown and described may be made within the scope of the claims without departing from the spirit of my invention.

I claim:

1. In a self-heating sad iron, a hollow body, a cover pivotally secured upon said body, a yielding locking member on one of said elements, means on the other element adapted to coöperate with said member for automatically locking said cover in its closed position, a handle on said cover for exerting a pressure thereon tending to move said cover to an open position whereby said member and means are released from each other and a burner located in said body. 70

2. In a self-heating sad iron, a hollow body, a burner located therein, a cover pivotally secured upon said body, locking means located interiorly of said body, a yielding locking member carried by said cover and arranged to extend into said body into engagement with said locking means whereby said cover is automatically locked in its closed position and means whereby said cover is moved relatively to said body to an open position and said locking means and member are released from each other. 85

3. In a self-heating sad iron, a hollow body, a burner located therein, a cover pivotally secured upon said body, a locking element located on the inside of said body, a dog carried by said cover and arranged to extend into said body and coöperate with said locking element to lock the cover in its closed position and means for maintaining 95 said dog and locking element in coöoperative engagement with each other. 100

4. In a self-heating sad iron, a hollow body, a burner located therein, a cover pivotally secured upon said body, a locking element located on the inside of said body, a dog movably mounted on said cover and arranged to coöperate with said locking element to lock the cover in its closed position, said dog having a portion projecting beyond 105 the outer surface of said cover and resilient means located exteriorly on said cover in engagement with the projecting portion of said dog whereby the latter is maintained in coöoperative engagement with said locking element. 110

5. In a self-heating sad iron, a hollow body, a burner located therein, a locking element located on the inside of said body, a cover pivotally secured upon said body and provided with an aperture, a dog movably mounted on said cover and extending through said aperture and arranged to coöperate with said locking element to lock the cover in its closed position and a plate secured upon said cover and spaced from the outer surface thereof, said plate engaging said dog whereby the latter is maintained in coöoperative engagement with said locking element. 120 125 130

6. In a self-heating sad iron, a hollow body having an interiorly located recess, a burner located in said body, a cover pivotally secured upon said body and provided 5 with an aperture, a dog extending through said aperture and arranged to coöperate with said recess to lock said cover in its closed position, transverse shoulders on said dog resting upon the exterior surface of said 10 cover and forming a pivot for said dog, and a resilient plate secured upon said cover and spaced from the outer surface thereof, said plate engaging said dog whereby the latter is maintained in coöperative engagement 15 with said recess.

7. In a self-heating sad iron, a hollow body, a burner located therein, a locking element located interiorly of said body, a cover hinged to said body about a horizontal pivot, 20 and resilient locking means carried by said cover and projecting beyond the inner sur-

face thereof and coöperating with said locking element to lock the cover in its closed position.

8. In a self-heating sad iron, a hollow 25 body, a burner located therein, a locking element located on the inside of said body, a cover pivotally secured upon said body and provided with an aperture, a plate secured upon said cover and spaced from the outer 30 surface thereof and a locking dog extending from said plate through said aperture and arranged to coöperate with said locking element to lock said cover in its closed position.

In testimony whereof I have hereunto set 35 my hand in the presence of two subscribing witnesses.

OTTO SPAHR.
